UNITED STATES PATENT OFFICE.

LAFE SWANK, OF ANDERSON, INDIANA, ASSIGNOR TO DWIGGINS WIRE FENCE COMPANY, OF ANDERSON, INDIANA, A CORPORATION OF INDIANA.

WIRE-FENCE MACHINE.

Application filed May 25, 1927. Serial No. 193,993.

The object of my invention is to provide certain improvements in details of construction by means of which stay wires may be automatically associated, in proper lengths, 5 with pairs of running wires in a wire fence fabric.

The accompanying drawings illustrate my invention. Fig. 1 is a perspective view of a machine embodying my invention; Fig. 2 10 is a fragmentary plan of the means for associating the stay wire pieces with the running wires, the running wires being shown in section and the stay wires being shown in a condition immediately preceding cutting 15 from the supply; Fig. 3 a fragmentary view similar to Fig. 2, the stay wires being shown in condition immediately following cutting from the supply and immediately preceding twisting; Fig. 4 a view similar 20 to Figs. 2 and 3 with the parts in the position immediately following twisting and just preceding advancement of the running wires and attached stay wires; Fig. 5 a fragmentary elevation of a running wire and the 25 two associated stay wires; Fig. 6 an elevation similar to Fig. 5 in a plane at 90 degrees therefrom; Fig. 7 a vertical section on line 7—7 of Fig. 2 with the parts in position immediately preceding cutting and bending of the stay wires; Fig. 8 a vertical section of 30 the parts shown in Fig. 7 with the parts in position immediately following cutting and bending of the stay wires; Fig. 9 an elevation 35 of the parts shown in Fig. 8 with said parts in the positions shown in Fig. 7; Fig. 40 10 a fragmentary elevation of a twister head and associated parts at the end of the twisting operation; Fig. 11 a plan, somewhat distorted, of the stay wire feeding and twisting 45 means and Fig. 12 an elevation of one of the stay wire holders and adjacent parts.

In the drawings 20 indicates the main frame through which the running wires 21 are threaded over suitable supports 22 and 45 advancing means 23, said parts being common and well-known in the trade and the details thereof forming no part of my present invention.

Each running wire is threaded axially 50 through a twister head 30, of well known form, said twister head having at its end two eccentric pins or shoulders 31, 31 spaced from the bore, through which the running wire passes, a distance slightly greater than 55 the diameter of the stay wire which is to be

attached to the running wire which passes through the bore.

Each twister head 30 is provided with a shank 35 which is journaled in the main frame 20 and in a bracket 36 secured thereto, 60 and each shank is provided with a pinion 37 which meshes with one set of teeth of a double rack 38 slidably mounted on the main frame. The other set of teeth of rack 38 meshes with a pinion 40 journaled on a cross 65 head 41 which is reciprocably mounted in a slot 42 in the main frame 20 and is connected by a link 43 with a lever 44 pivoted at 45 on the main frame and intermittently reciprocated by a cam 46 on shaft 47 journaled in the main frame. Pinion 40 also meshes with a fixed rack 50 mounted on the main frame 70 20.

Arranged between each pair of twister heads is a two-part stay-wire holder, shown 75 in detail in Fig. 12. This holder comprises a stationary portion 55 across the face of which is formed a half groove 56 having a diameter slightly greater than the diameter of the stay wire 32 which is to be used. Associated with the portion 55 is a hinged portion 57 the inner face of which is likewise provided with a transverse groove 58 which registers with groove 56. At the receiving end of the groove or wire guide 56—58 it is 80 flared outwardly, as indicated in Fig. 12. Portion 57 is yieldingly urged against portion 55 by a spring 59.

Leading to each of the stay wire holders just described but spaced therefrom by an 90 intervening twister head is a guide tube 60 at the end of which is a cutting die 61 through which the stay wire is threaded, said die being so placed and directed that a stay wire projected through the guide tube will 95 pass between the running wire and one of the twisting pins 31 of the adjacent twister head and will pass from thence into and through the associated stay wire holder and from thence between the next running wire 100 and the other twister pin 31 of the next twister head, as clearly shown in Fig. 2.

Each stay wire is projected through its guide tube 60, an amount sufficient to form a 105 stay wire portion, by feeding means which consists of two friction wheels 62 and 63, each wheel 62 being of a diameter selected to provide the requisite stay wire length. The several feed wheels 62 are carried by a shaft 64 which is intermittently advanced by a 110

ratchet mechanism 65 actuated by a lever 66 actuated by a cam 67 on shaft 47. Friction shoes 70 are pressed against shaft 64 by springs 71 each backed by a cam 72 which ⁵ may be swung into or out of action by an arm 73.

Arranged alongside of the series of twister heads is a rock shaft 75 upon which is mounted a series of cutter and bender heads 10 76, one for each twister head. Each bender head carries a combined cutter and bender finger 77 and a bender finger 78 which fingers are so spaced and arranged that, as shaft 75 is rocked (in a counter-clockwise direction, 15 Fig. 7) finger 77 will cooperate with die 61 to cut the stay wire running therethrough and to then bend said stay wire down upon an inclined surface 79 on the twister head 30, and finger 78 will engage the free end of 20 the associated stay wire 32 and bend it down upon the downwardly inclined surface 80 on twister head 30 diametrically opposite surface 79.

Shaft 75 is intermittently rocked by 25 means of a pitman 90 connected to a lever 91 actuated by a cam 92 on shaft 47.

The operation is as follows:

The twister heads being in the positions indicated in Fig. 2, the ratchet mechanism 30 65 will actuate the several stay wire feeder wheels 62 to project through each tube 60 an amount of stay wire sufficient to bridge the space between the adjacent pair of running wires and to furnish, beyond each of 35 said running wires, a sufficient quantity of stay wire for the twist or wrapping of the stay wire about the adjacent running wire, each stay wire being projected through a two part stay wire holder 55—57.

40 Shaft 75 will then be rocked to cause, in the manner already described, a cutting and bending of stay wire portions, each supported in its two part holder, and will then be returned to the position shown in Fig. 7.

45 Thereupon cross head 41 will be reciprocated so as to rotate the twister heads 35 a sufficient number of times to twist the free ends of the stay wire sections around the adjacent running wires as illustrated in

50 Figs. 5, 6 and 10. Thereupon the running wire feeding mechanism 23 will be actuated to advance the running wires one step in the machine, the yielding sections 57 of the stay wire holders yielding to permit the with-

drawal of the stay wire sections therefrom. While the running wires are being thus advanced the stay wires are being again projected in the manner already described and the operation is repeated.

65

I claim as my invention:

1. In a machine for producing wire fabric, the combination with means for supporting and forwarding a series of running wires, a series of stay-wire twister heads through each of which a running wire passes, means for intermittently rotating the said twister heads, and means for associating stay wires with the running wires through the medium of the twister heads, said means comprising, for each pair of running wires, a two-part holder arranged between said pair of running wires and formed to receive, guide and support a stay wire, a series of stay wire guides each leading to a holder but spaced therefrom by a twister head, a series of stay-wire cutters, one adjacent each twister head and arranged to cut a portion of a stay wire from its supply, and means for intermittently actuating said stay-wire cutters.

60

2. In a machine for producing wire fabric, the combination with means for supporting and forwarding a series of running wires, a series of stay-wires twister heads through each of which a running wire passes, means for intermittently rotating the said twister heads, and means for associating stay wires with the running wires through the medium of the twister heads, said means comprising, for each pair of running wires, a two-part holder arranged between said pair of running wires and formed to receive, guide and support a stay-wire, a series of stay-wire guides each leading to a holder but spaced therefrom by a twister head, a series of stay-wire cutters and benders, one adjacent each twister head and arranged to cut a portion of a stay wire from its supply and to bend the adjacent overlapped stay wire ends into association with the adjacent twister head, and means for intermittently actuating said stay wire cutters and benders.

65

In witness whereof, I have hereunto set my hand at Anderson, Indiana, this 23rd day of May A. D. one thousand nine hundred and twenty-seven.
